[57] CLAIM

The ornamental design for a toothpaste tube or the like, as shown and described.

DESCRIPTION

FIG. 1 is a top perspective view of a toothpaste tube or the like showing my new design;

FIG. 2 is a top plan view thereof, the bottom being substantially a mirror image of that shown; and

FIG. 3 is a cross sectional view taken through lines 3—3 of FIG. 2.

FIG. 1

FIG. 2

FIG.3
